RIVETING MACHINE

Charles W. Sinclair, Detroit, Mich., assignor to
Kelsey-Hayes Wheel Corporation, Detroit,
Mich., a corporation of New York

Application August 18, 1930. Serial No. 476,195

18 Claims. (Cl. 78—16)

This invention relates generally to riveting machines and refers more particularly to apparatus for riveting the spokes of vehicle wire wheels.

5 One of the principal objects of this invention is to provide a machine for the purpose specified above capable of more expediently riveting the spokes of a wire wheel in place with the minimum amount of manual attention, thereby materially expediting production and appreciably reducing the cost of manufacture.

The invention provides for expediting production and reducing the cost of manufacture by introducing a machine having mechanism automatically operable to rivet a plurality of spokes simultaneously, together with means for indexing the wheel assembly for automatically and successively advancing the spokes opposite the riveting punches.

20 Another novel feature of this invention which contributes materially to the reduction in cost of manufacture as well as facilitating production resides in the provision of a plurality of wheel supporting standards designed to support a corresponding number of wire wheel assemblies and mounted upon the machine for movement independent of each other, into and out of operative relation with the machine to alternatively position the wheel assemblies supported thereby in registration with the riveting means. The foregoing construction is such that while the spokes of one wheel are being riveted by the apparatus, another wheel assembly to be operated upon is set up upon another standard with result that 25 the latter may be immediately moved into operative position as soon as the succeeding wheel is completed. Thus, it will be seen that with the present invention the riveting operation is substantially continuous since practically no time is lost in setting up the work.

With the foregoing as well as other objects in view, the invention resides in the novel details of construction which will be made more apparent as this description proceeds, especially 45 when considered in connection with the accompanying drawings, wherein:

Figure 1 is a vertical sectional view through a machine constructed in accordance with this invention.

50 Figure 2 is a sectional view taken substantially on the line 2—2 of Figure 1.

Figure 3 is a sectional view taken substantially on the line 3—3 of Figure 1.

55 Figure 4 is a fragmentary top plan view partly in section of the wheel supporting structure.

Figure 5 is a sectional view taken substantially on the line 5—5 of Figure 1.

The riveting machine forming the subject matter of this invention is designed to rivet the outer ends of wire spokes of a vehicle wire wheel having a rim 10 and a hub shell 11 arranged concentric with the rim. The hub shell is provided with a barrel 12 having an inner axially extending section 13 spaced inwardly from the rear end portions of the shell and provided with an inwardly extending flange 14 serving to attach the wheel assembly to the inner wheel hub (not shown). The front and rear portions of the hub shell are provided with a plurality of circumferentially spaced openings for receiving the inner ends of the front and rear spokes which serve to connect the hub shell to the rim. The front spokes extend from the rear edge of the rim base to the forward end of the shell, while the rear spokes 15 extend from the front edge of the rim to the rear end of the shell. The rear spokes are provided with semi-spherical heads at the inner ends adapted to engage correspondingly spaced seats formed in the hub shell barrel adjacent the rear end portion thereof. The outer end portions of the rear spokes on the other hand, are provided with annular shoulders 16 adapted to engage the base of the rim and are further provided with tenons 17 having their axes inclined to the axes of the spokes so as to extend radially through the base of the rim. In this connection it should be understood that the semi-spherical enlargements on the inner ends of the spokes and the annular shoulders adjacent the outer ends thereof are at fixed distances apart with the result that when the enlargements and shoulders engage the hub shell and rim, respectively, concentricity of the latter is insured. The rear spokes are arranged in pairs with the spokes of each pair extending outwardly from the hub shell to the rim and crossing intermediate their ends.

The machine illustrated herein comprises generally a pair of standards A and B having means for supporting and clamping a pair of wire wheel assemblies thereon in substantially a horizontal plane. Each of the standards A and B are hingedly mounted upon opposite sides of the frame for swinging movement in substantially a horizontal plane and are adapted to be moved alternatively into operative position with the riveting punches and spoke clamping means to be more fully hereinafter described. The supporting and clamping means upon each standard for the wire wheel assemblies operate independent 105 110

of each other to clamp the wire wheels in position with the result that when the standard A is in operative position with the machine, as shown in Figure 4, a wheel assembly to be operated upon 5 may be set up upon the standard B. The arrangement is such that when all of the spokes upon the wheel assembly carried by the standard A have been riveted, the latter standard may be swung to inoperative position and the wheel 10 assembly supported by the standard B immediately moved into operative position. During the time required to rivet the spokes of the wheel supported on the standard B, the operator is free to remove the finished wheel from the standard 15 A and assemble another wheel to be operated upon with the standard so that the latter can be immediately moved into operative position as soon as the wheel on the standard B has been completed. Thus, it will be observed that by 20 reason of the above construction, production is materially facilitated since practically no time is lost in setting up the work and moving the same into operative relation with the machine.

In order to expedite the riveting operation 25 and thereby further facilitate production, the riveting mechanism illustrated generally by the reference character C is designed to rivet a pair of spokes simultaneously. The riveting mechanism comprises a pair of radially movable punches 30 D and E so arranged with respect to each other as to engage the outer ends of a pair of spokes and simultaneously rivet the same to the rim. The punches D and E are mounted for movement in a substantially horizontal plane toward and 35 away from the rim as a unit and are adapted to be actuated in timed relation to the indexing mechanism F for intermittently rotating the wheels carried by the standards A and B to successively position each pair of spokes in operative 40 relation to the punches.

In order to prevent bending of the spokes during the riveting operation, I provide a pair of spoke gripping jaws G movable in a plane substantially transverse to the plane of movement 45 of the punches and adapted to grip the spokes adjacent the enlargements formed thereon for urging the latter against the inner face of the rim during the riveting operation. The gripping jaws G are operated in timed relation to the 50 operation of both the riveting punches and wheel assembly so as to move into clamping engagement with a pair of spokes subsequent to movement of the wheel assembly to position the pair of spokes opposite the riveting punches and prior 55 to the actuation of the punches to rivet the ends of the spokes.

In detail, the riveting machine illustrated herein is adapted for use in connection with a conventional type of punch press and comprises a 60 base 20 having a substantially horizontal support 21 upon which the riveting punches D and E are slidably mounted for movement axially of the spokes of the wheel and in a substantially horizontal plane. The punches D and E are slidably 65 mounted within a pair of blocks 22 which in turn are rigidly secured within recesses 23 formed in the inner ends of the die blocks 24. The latter are slidably mounted upon the gibs 25 carried by the support 21 and so arranged as to compel 70 movement of the blocks 24 radially of the axis of the wheel assembly to be operated upon. The blocks 22 are secured within the recesses 23 of the die blocks 24 in spaced relation to the walls 25' of the latter which are inclined rearwardly 75 as shown in Figure 1. Disposed within the space

between the blocks 22 and walls 25' are suitable wedge members 26 having substantially vertical walls 27 adjacent the outer walls of the blocks 22 and engaging the outer ends of the punches D and E. The outer walls of the wedge members 26 on the hand are inclined at an angle corresponding to the inclination of the walls 25 and are slidably engageable therewith so as to provide an efficient and adjustable backing for the punches. The construction is such that movement of the wedge members 26 upon the inclined side walls 25', hereinbefore described, effects a longitudinal movement of the front wall of the wedge members and since this wall engages the inner ends of the punches, the latter are adjusted relative to the blocks 22. The wedge members 26 are normally held in engagement with the outer ends of the punches by means of suitable clamps 29 having spaced cam surfaces 30 and 31, respectively engaging the blocks 24 and wedge-shaped members 26. The clamps are preferably secured to the die blocks 24 by means of threaded elements 32 having head portions engaging the top surface of the clamps and having shank portions extending through clamps intermediate the cam surfaces thereof and threadedly engaging the blocks 24. The punches D and E are normally held from axial movement relative to the blocks 22 by means of suitable set screws 33 threadedly engaging the blocks and having the lower ends 34 engaging suitable inwardly inclined surfaces 34 on the punches D and E. Thus, it will be seen that when the parts are in the position shown in Figure 1, the punches D and E are prevented from outward movement by engagement with the inner walls of the wedge members 26 and are prevented from inward movement by means of the set screws 33 engaging the cam surface 34.

For actuating the punches D and E, I provide a vertically reciprocable head 35 operatively connected to a suitable punch press (not shown) and having a pair of cam members 36 secured to the under surface thereof as at 37 and projecting downwardly therefrom. The cam members 36 are identical in construction and are provided with cam surfaces 38 at the inner sides thereof adapted to engage suitable rollers 39 carried by the die blocks 24 adjacent the outer ends thereof. The cam surfaces 38 are designed to engage the rollers 39 upon downward movement of the head 35 and move the die blocks inwardly radially of the axis of the wheel to engage the punches D and E, carried by the blocks, with the outer ends of a pair of the vehicle wheel spokes. Outward movement of the die blocks 24 and punches D and E carried thereby is effected by means of pins 39' carried by the outer ends of the die blocks 24 and engageable within suitable recesses 40 formed in the cam members 36. The recesses 40 conform to the shape of the cam surfaces 38 so that upon upward movement of the holder 35 and cam 36, the inner walls 41 of the recesses engage the pins 39' and owing to the inclination of the walls 41, as shown in Figure 1, the pins 39' will be moved outwardly and since the pins are carried by the die blocks 24, the latter will be moved in corresponding directions to inoperative positions. The cam members 36 are accurately guided throughout their movement by means of rollers 41' carried by a stationary part 42 of the machine and engageable with the outer surfaces of the cam members 36. As previously stated, both the cam members 36 are identical in construction with the result that the die blocks 24 are actuated simultaneously to engage the 150

punches D and E with the spokes of the wheel assembly.

As briefly outlined above, the spokes of the wheel assembly are rigidly clamped against movement prior to riveting the same by the clamping means G. The clamping means G comprises a pair of blocks 42 and 43 slidably mounted upon a stationary part 44 of the machine for movement in a substantially vertical plane. The block 42 is positioned above the spokes of the wheel assembly while the block 43 is arranged below the spokes of the wheel assembly in alignment with the block 42 and cooperates with the latter to engage a pair of spokes for a substantial distance inwardly of the rim member 10 of the wheel assembly. As will be observed from Figure 1, the clamping block 43 does not directly engage the spokes of the wheel assembly, but on the other hand actuates a suitable rocker 45 pivotally mounted as at 46 to a stationary part of the machine at a point spaced outwardly from the plane of movement of the die blocks 42 and 43. The inner end of the rocker 45 is provided with an upwardly extending projecting portion 47 adapted to project through suitable slots 48 formed in the supporting member 49 for the wheel assembly to be more fully hereinafter set forth. The above construction is such that movement of the block 43 upwardly causes a corresponding movement of the rocker 45 to extend the projection 47 through the slot 48 into engagement with a pair of the spokes of the wheel assembly. When, on the other hand, the block 43 is in its lowermost position, the projection 47 on the rocker 45 assumes a position below the supporting member 49 so as not to interfere with rotation thereof to position the spokes of the wheel assembly opposite the punches D and E. In order to compel the rocker 45 to follow the block 43 during movement thereof, the latter is provided with a suitable pin 50 having a portion engaging within a slot 51 formed in the free end of the rocker 45. From the foregoing, it will be seen that the block 43 engages the free end of the rocker 45 to move the same into engagement with the spokes, thereby materially increasing the leverage with the result that the spokes are clamped by the blocks with a relatively great force.

For moving the blocks 42 and 43 toward each other to rigidly clamp a pair of spokes therebetween, I provide a pair of levers 52 and 53 pivotally mounted intermediate the ends thereof upon suitable shafts 54 carried by the frame of the machine. The inner ends of the levers 52 and 53 engage respectively within suitable recesses formed in the blocks 42 and 43, while the outer ends of the levers 52 and 53 are provided with spaced rollers 55 and 56 adapted to engage opposite sides of the double acting cam members 57. The double acting cam members 57 are rigidly secured to a plate 58 mounted for oscillation in a substantially vertical plane about the shaft 59. The disposition of the cam members 57 upon the plate 58 is accurately determined and the opposed cam surfaces 60 and 61 of each cam member 57 for respectively engaging the rollers 55 and 56 are so designed, that movement of the plate 58 in a clockwise direction causes the lever 52 to move in a counter-clockwise direction and the lever 53 in a clockwise direction about the shafts 54 and thereby causes the clamping blocks 42 and 43 to move toward each other for rigidly clamping a pair of spokes of the wheel assembly. When, on the other hand, the plate 58 is moved

in a counter-clockwise direction, the lever 52 is caused to move in a counter-clockwise direction and the lever 53 in a clockwise direction about the shafts 54 with the result that the inner ends of the levers will be moved away from each other causing the clamping blocks 42 and 43 to move to their inoperative positions.

The plate 58 is actuated by the vertically reciprocal head 35 by means of an adjustable tie rod 62 having the upper end thereof pivotally connected to the head 35 and the lower end pivotally connected to a lug 63 projecting beyond the outer edge of the plate 58. While the punches D and E and clamping blocks 42 and 43 are both actuated by the head 35, it should be understood that the operative connections, previously described, between the punches, spoke clamping means and head 35 are so designed that the clamping blocks function to rigidly clamp a pair of spokes in position prior to the operation of the punches D and E to rivet the spokes. In other words, the construction is such that upon initial downward movement of the head 35 the plate 58 is oscillated about the shaft 59 to move the clamping means G in clamping engagement with a pair of spokes of the wheel assembly. Continued downward movement of the head 35 registers the cam surfaces 38 with the rollers 39 to move the punches radially inwardly into engagement with the outer ends of the spokes as previously set forth.

Referring now more in detail to the particular construction of the standards A and B, previously described, for alternatively positioning wheel assemblies in operative relation with the riveting punches and clamping means, it will be noted from Figure 2 of the drawings that the standards A and B are carried by the free ends of a pair of arms 65 having the opposite ends pivotally connected as at 66 to the frame of the machine upon opposite sides of the same for swinging movement in a substantially horizontal plane. The configuration of the arms 65 is such and the location of the pivots 66 for connecting the arms to the frame is so determined that when the arms are moved inwardly to operative position, a line drawn through the axes of the pivots 66 passes through the axis of the standard in operative position. The standards are preferably tubular in shape and project through a slot 67 in the base 20 of the machine as clearly shown in Figures 1 and 2.

Journalized within the tubular standards A and B and movable therewith are suitable drive shafts 68 having their lower ends adapted to be operatively connected to the indexing mechanism F and having the upper ends thereof secured to the supports 49 which are journaled upon the upper ends of the sleeve-like standards A and B by means of the roller bearings 69. The supports 49 are preferably circular and are provided at the periphery thereof with a plurality of upwardly extending pins 70 arranged circumferentially and adapted to engage the tire retaining flanges upon the rims 10 of the wheel assemblies to support the same. The supports 49 for the wheel assemblies are further provided with annular upwardly extending projections 71 adapted to engage the rear annular flanges upon the hub shells 11 for positioning the latter concentric with the rims 10.

The hub shells 11 of the wheel assemblies are rigidly clamped upon each of the standards by means of chucks 72 having hub portions 73 journaled upon shafts 74 extending upwardly from

the supports 49 co-axially therewith. The chucks 72 are adapted to engage the rear ends of the inner hub shell parts 13 and are provided with tapered annular surfaces 75 adapted to engage the inner spherical portions of the spokes for clamping the same to the hub shells. The chuck 72 of each standard is preferably operated by fluid pressure through the intermediary of a fluid cylinder and piston assembly (not shown) 10 adapted to be secured to the lower ends of each standard. The arrangement is such that the clamping means carried by each standard may be operated independent of the other to rigidly clamp the wheel assemblies in position upon the 15 standards. The wheel assemblies are positioned circumferentially relative to the punching and clamping mechanisms by means of a suitable device 77 secured to each of the supports 49 and having a projection 78 engageable within the 20 valve stem holes formed in the base portions of the vehicle rims 10. The devices 77 function to initially position the wheel assemblies circumferentially upon the supports 49 so that upon predetermined step-by-step movements of the 25 support 49, pairs of spokes of the wheel assemblies will be successively moved into operative position relative to the clamping and punching means hereinbefore described. Thus, from the foregoing it will be observed that the wheel 30 assemblies are supported upon each of the standards in a substantially horizontal plane and concentricity of the rims and hub shells of the wheel assemblies is insured, since the spokes are all of a fixed length and the chuck 72 engages 35 the inner spherical portions of the spokes to clamp the same to the inner surfaces of the hub shells, while the clamps G engage the spokes inwardly from the shoulders on the outer ends thereof for clamping the said shoulders into engagement with the base portions of the rims. 40

For rotating the wheel assemblies by a step-by-step movement to accurately position each pair of spokes of the wheel assemblies in alignment with the punches D and E and as a consequence, 45 in a position to be engaged by the clamping means G, any suitable indexing mechanism may be employed, but as shown herein, I provide indexing mechanism commonly known in the trade as Geneva movement. The Geneva gearing employed herein comprises a pair of star wheels 78 secured 50 to the lower end portions of each of the shafts 68 and adapted to mesh with the cooperating driving and locking wheel 79 which is driven from the source of power by means of the gearing designated generally by the reference character 80. 55 The actuating wheel 79 is rotated in timed relation to the operation of the punches and clamping means so that the spokes of the wheel assemblies will be accurately positioned relative to the punches and clamping means prior to the operation 60 thereof.

The actuating wheel 79 is provided with a locking member 81 adapted to conform to the semi-circular recesses 82 in the star wheel teeth 83 for locking the star wheel against movement until the pin 84 on the wheel 79 engages within the slots 85 between the teeth 83 at which time the star wheel will be advanced a predetermined distance depending upon the dimension of the teeth. The 65 extent of rotation of the star wheel is determined by the location of the spokes of the wheel assembly and is so selected that when the star wheel rotates the distance of one tooth, a pair of spokes will be advanced to operative position. 70

75 In order to insure accurate positioning of the

standards A and B relative to the machine, the former are adjustably mounted upon the free ends of the arms 65. In detail, each of the standards is provided with an outwardly extending projection 86 slidably engaging the outer end portions of the arms 65. Accurate adjustment of the standards is effected by suitable threaded elements 87 threadedly engaging an upwardly extending projection 88 on the arms 65 and operatively connected as at 89 to the outer ends of the projections 86. The standards are prevented from accidental disengagement from the machine by means of a suitable latch member 90 pivotally connected at the outer end thereof to a stationary part of the machine as at 91 and having the inner end thereof engageable with the upwardly extending projections 88 on the arms 65. 80

From the foregoing, it will be observed that each of the standards A and B operate entirely independent of each other to operatively clamp a wheel assembly in place and are each capable of being independently swung as a unit from operative position with the machine to points spaced from the machine. Thus, it will be seen that when one of the standards is in operative position with the machine and during the time the wheel assembly supported thereby is being operated upon, the other standard may be manipulated to clamp another wheel assembly in place. The construction is such that when the wheel assembly supported by the standard A has been completed, the operator merely manipulates the latch 90 and moves the standard A into inoperative position. As the standard A is being swung to inoperative position, the standard B may be swung to operative position with the result that practically no time is lost in feeding the work to the machine. In this connection it is to be noted that inward movement of the standards A and B toward operative position is limited by engagement of the outer ends of the arms 65 with the frame 44 of the machine as indicated by the reference character 92. 90

What I claim as my invention is:

1. In a riveting machine for vehicle wheels, the combination with a base and riveting means supported by the base and operable to secure parts of the wheel assembly together, of means for supporting a plurality of wheel assemblies from the base independent of each other for rotation about their axes and with the portions thereof to be riveted in the plane of movement of the riveting means, means for mounting the supporting means upon the base permitting swinging movement of the wheel assemblies toward and from the machine for alternatively registering the same with said riveting means and means operable upon movement of the supporting means into operative relation to the riveting means for indexing the wheel assembly on said supporting means to position the portions of the assembly to be riveted opposite the riveting means. 100

2. In a riveting machine for vehicle wheels, the combination with a base and riveting means supported by the base and operable to secure parts of the wheel assembly together, of a plurality of supporting devices each having means for rotatably clamping a wheel assembly thereto with the part to be riveted in the plane of movement of the riveting means, means connecting said devices to the base permitting swinging movement thereof relative to the machine independent of each other and thereby permitting the wheel assemblies supported thereby to be alternatively registered with the riveting means and means operable upon movement of the supporting means 110

- into operative relation to the riveting means for periodically rotating the wheel assembly to position the portions to be riveted opposite said riveting means.
5. In a riveting machine for vehicle wheels, the combination with a base and riveting means supported thereby for riveting parts of the wheel assembly together, of a plurality of supporting devices each having means for clamping a wheel assembly thereto with the part to be riveted in the plane of movement of the riveting means, means pivotally connecting each of said devices to the base permitting the devices to be moved independent of each other relative to the machine and thereby permitting the wheel assemblies supported thereby to be alternatively registered with the riveting means, indexing mechanism carried by the base and cooperating indexing means carried by each of said devices adapted to register with the indexing mechanism aforesaid for rotating the wheel assemblies with a step-by-step movement.
6. In a riveting machine for vehicle wheels, the combination with a base and riveting means supported by the base for riveting parts of the wheel assembly together, of a plurality of wheel assembly supporting devices mounted upon the base for swinging movement independent of each other toward and from the riveting means to alternatively position the wheel assemblies supported thereon in operative relation with the riveting means, independently operable means associated with each device for rotatably clamping a wheel assembly thereon in a position to be registered with the riveting means whereby a wheel assembly may be assembled upon one of said devices during the time another wheel assembly is being operated upon, means for periodically rotating the wheel assembly being operated upon by the riveting means to index the said assembly, and means carried by a fixed part of the machine for clamping the parts of the wheel assembly to be riveted during the interval of rest of said assembly.
5. In a riveting machine for wire wheels, the combination with a base and riveting means supported thereby for riveting the spokes of the wheel assembly to the rim member of the wheel assembly, of a plurality of supporting devices each having independently operable means for clamping a wheel assembly thereto with the hub member thereof in concentric relation to the rim member of the same and with the outer ends of the spokes to be riveted in the plane of movement of the riveting means, means hingedly connecting each of said devices to the base permitting independent swinging movement thereof relative to the machine and thereby permitting the wheel assemblies supported thereby to be alternatively registered with the riveting means, indexing mechanism carried by the base and cooperating indexing means carried by each of the devices adapted to register with the indexing mechanism aforesaid for automatically indexing the wheel assemblies when in operative relation with the riveting means to successively advance the spokes in registration with the riveting means.
6. In a riveting machine for vehicle wheels, the combination with a base and riveting means supported by the base for riveting parts of a wheel assembly together, of a plurality of independent supporting devices mounted for movement alternatively into and out of operative relation with the riveting means, means associated with each of said devices for rotatably supporting a wheel assembly with the parts to be riveted in registration with the riveting means, and means operable upon movement of the wheel assembly into operative relationship to the riveting means for indexing said assembly to successively bring the parts thereof to be riveted opposite the riveting means.
7. In a riveting machine for vehicle wire wheels, the combination with a base and riveting means supported by the base for riveting the spokes of the wheel assembly to the rim member of the wheel assembly, of a plurality of supporting devices mounted for movement alternatively into and out of operative relation with the riveting means and each of said devices having means for rotatably supporting a wheel assembly with the spokes to be riveted in the plane of the riveting means for registration therewith, and indexing mechanism for the wheel assemblies carried by said supporting devices.
8. In a riveting machine for vehicle wire wheels, the combination with a base and riveting means supported by the base for riveting spokes of a wheel assembly to the rim member of the wheel assembly, of a supporting device mounted for movement into and out of operative relation with the riveting means, means for rotatably supporting a wheel assembly on the support with the spokes to be riveted in the plane of the riveting means for registration therewith, and indexing mechanism for the wheel having cooperating separable parts carried respectively by the base and supporting device and engageable for indexing the wheel upon movement of the support into operative relation with the riveting means.
9. In a riveting machine for vehicle wire wheels, the combination with a base and riveting means supported by the base for riveting spokes of a wheel assembly to the rim member of the wheel assembly, of a plurality of supporting devices mounted for movement into and out of operative relation with the riveting means and each of said devices having means for rotatably supporting a wheel assembly with the spokes to be riveted in the plane of the riveting means for registration therewith, indexing mechanism for the wheel assemblies having cooperating separable parts carried respectively by the base and supporting devices aforesaid, and means for adjusting the wheel assemblies relative to the supporting device to insure proper positioning of the wheel assemblies relative to the riveting means.
10. In a riveting machine for wire wheels, the combination with a base, of means for supporting a wheel assembly from the base, means for simultaneously riveting a plurality of spokes of the wheel assembly to the rim member thereof including a plurality of radially movable punches, means for gripping the spokes prior to the riveting operation including a pair of members mounted for movement in a direction transverse to the direction of movement of the punches, a reciprocable head having cam surfaces for simultaneously actuating the punches, and means also actuated by said head for operating the gripping means aforesaid in timed relation to the operation of said punches.
11. In a riveting machine for wire wheels, the combination with a base, of means for supporting a wheel assembly from the base, means for simultaneously riveting a plurality of spokes of the wheel assembly to the rim member thereof including a plurality of radially movable punches,

- means for gripping the spokes prior to the riveting operation including a pair of members mounted for movement in a direction transverse to the direction of movement of the punches, a 5 reciprocable head having cam surfaces for simultaneously actuating the punches, and means for actuating the gripping means in timed relation to the punches including an oscillatable cam operatively connected to the head for actuation 10 thereby.
12. In a riveting machine for wire wheels, the combination with a base, of means for supporting a wheel assembly from the base, means for riveting a spoke of the wheel assembly to the rim 15 member thereof including a radially movable punch device, means for gripping the spoke prior to the riveting operation including a pair of co-operating clamping members, a reciprocable head having a cam surface engageable with the punch 20 device for actuating the same, an oscillatable cam member having cam surfaces for operating the cooperating members aforesaid, and a connection between the oscillatable cam and head for actuating the cam in timed relation to the 25 movement of the head for operating the punch device.
13. In a riveting machine for vehicle wheels, the combination with a base, a frame member fixed relative to the base and riveting means 30 supported by the base for riveting parts of a wheel assembly together, of a plurality of wheel assembly supporting devices mounted upon the base for movement independent of each other toward and from the riveting means to alternatively position the wheel assemblies carried thereby in operative relationship to the riveting means, means for clamping a wheel assembly to each of said devices permitting rotation of the wheel assemblies about their axes, means operable upon movement of said devices into operative 35 relation with the riveting means for indexing the wheel assemblies to successively position the portions thereof to be riveted opposite the riveting means, and means carried by the fixed frame member and engageable with the portions of 40 the wheel assemblies to be riveted during the interval of rest of the latter for clamping the portions aforesaid thereof in position opposite the riveting means.
14. In a riveting machine for vehicle wheels, the combination with a base, a frame member fixed relative to the base, and riveting means supported by the base for riveting parts of the wheel assembly together, of a wheel assembly 45 supporting device mounted upon the base for movement into and out of operative relation to the riveting means, means for rotatably supporting a wheel assembly upon said device in a position whereby movement of the device into operative relation with the riveting means registers the parts to be riveted of said assembly with the riveting means, and opposed clamping members slidably mounted upon said fixed frame member for clamping the parts of the wheel 50 assembly to be riveted therebetween prior to the riveting operation.
15. In a riveting machine for vehicle wheels, the combination with a base, a frame member fixed relative to the base and riveting means supported by the base for riveting parts of the wheel assembly together, of a wheel assembly supporting device mounted upon the base for swinging movement into and out of operative relation 55 with the riveting means, means associated with the device for rotatably clamping a wheel assembly thereto in a position whereby movement of the device into operative relation with the riveting means registers the parts to be riveted with said riveting means, means operable upon positioning the wheel assembly into operative relation with the riveting means for periodically rotating the wheel assembly to index the same, means mounted upon the fixed frame member and operable during the interval of rest of the wheel assembly and in timed relation to the riveting means for clamping the parts of the wheel assembly to be riveted. 60
16. In a riveting machine for vehicle wheels, the combination of a base having an upright member provided with an opening therethrough and means for riveting parts of the wheel assembly together including a punch mounted upon one side of the fixed frame member in registration with the opening therethrough, a wheel assembly supporting device mounted upon the base on the opposite side of the upright frame member for movement into and out of operative relation with the riveting means, means for clamping a wheel assembly to the device in a position wherein the portions of the wheel assembly to be riveted lie in a plane common to the plane of the punch and wherein a portion of the wheel assembly extends through said opening when the device is moved in operative relation to the riveting means, and means arranged on the same side of the upright member as said punch for clamping the parts to be riveted prior to the punching operation. 65
17. In a riveting machine for vehicle wheels, the combination of a base having an upright portion provided with an opening therethrough, means supported upon one side of the upright portion in registration with the opening therethrough for riveting parts of the wheel assembly together, a wheel assembly supporting device mounted upon the base on the opposite side of the upright portion for movement into and out of operative relation to the riveting means, means for rotatably clamping a wheel assembly to said device in a position wherein the parts to be riveted lie in a common plane with the riveting means and wherein a portion of the wheel assembly extends through the opening upon movement of the device in operative relation to the riveting means, means for indexing the wheel assembly, and means arranged upon the same side of the upright portion as the riveting means for clamping the parts to be riveted prior to the operation of said riveting means. 70
18. In a riveting machine for vehicle wheels, the combination with a base and riveting means supported by the base for riveting parts of the wheel assembly together, of a plurality of wheel assembly supporting devices mounted upon the base for movement independent of each other toward and from the riveting means to alternatively position the wheel assemblies supported thereby in operative relation with the riveting means, means for rotatably clamping a wheel assembly to each device in a position wherein the parts of the wheel assemblies to be riveted lie in the same plane as the riveting means, and means for indexing each wheel assembly when the same is in operative relationship to the riveting means. 75
